UNITED STATES PATENT OFFICE.

WILLIAM D. WATKINS, OF SAN JOSE, CALIFORNIA, ASSIGNOR TO WATKINS MANUFACTURING CO., OF SAN JOSE, CALIFORNIA, A CORPORATION.

TELEPHONE SELECTING APPARATUS.

No. 859,534.

Specification of Letters Patent.

Patented July 9, 1907.

Application filed April 30, 1906. Serial No. 314,481.

To all whom it may concern:

Be it known that I, WILLIAM D. WATKINS, a citizen of the United States, residing at San Jose, in the county of Santa Clara and State of California, have 5 invented a new and useful Telephone Selecting Apparatus, of which the following is a specification.

This invention relates to selective signaling systems, and has for its principal object to provide mechanism of novel construction, whereby the local circuits of 10 any desired telephone may be placed in communication with the main line while the circuits of all the remaining subscribers on the line are cut out.

A further object of the invention is to provide a circuit closing member that is arranged to receive a step 15 by step movement toward circuit closing position, and to provide a novel means for guiding said member during its movement.

A still further object of the invention is to provide a novel form of electro-magnetically actuated circuit 20 closer which, after a predetermined number of operations, is allowed to move by gravity into engagement with the circuit controlling contacts.

With these and other objects in view, as will more fully hereinafter appear, the invention consists in 25 certain novel features of construction and arrangement of parts, hereinafter fully described, illustrated in the accompanying drawings, and particularly pointed out in the appended claims, it being understood that various changes in the form, proportions, 30 size and minor details of the structure may be made without departing from the spirit or sacrificing any of the advantages of the invention.

In the accompanying drawings:—Figure 1 is a front elevation of a selecting device constructed in accordance with the invention, the lid or cover of the inclosing casing being removed. Fig. 2 is a vertical sectional view of the same on the line 2—2 of Fig. 1. Fig. 3 is a detail perspective view of the guiding device for the circuit closing member. Fig. 4 is a similar view of the upper end of the circuit closing member. Fig. 5 is a detail plan view, partly in section, showing the contacts which the circuit closer engages while in normal position. Fig. 6 is a side elevation drawn to an enlarged scale, and illustrating the contacts which are engaged at the end of the selecting operation. Fig. 7 is a diagram showing the wiring connections.

Similar numerals of reference are employed to indicate corresponding parts throughout the several 50 figures of the drawings.

The apparatus forming the subject of the present invention is designed principally for use in connection with telephone lines, although it may be employed for signaling circuits generally.

Each telephone on the line is equipped with one of 55 the selecting devices forming the subject of the present invention, and these are placed under the control of the operator at central, who by closing the circuit a number of times corresponding to the number of the sub-station desired, may connect that station with the 60 line to the exclusion of all other stations along the line.

The mechanism is preferably arranged within a suitable casing 10 which may be placed at one side of the telephone, or at any other convenient point, or the mechanism may be placed within the switch box of 65 the telephone, if desired.

Arranged within the casing 10 is an electro-magnet 11, having a polarized armature 12 pivoted on a bracket 13 at a point between the two poles of the electro-magnet. The armature is extended in the form of an arm 70 15 to the outer end of which is pivoted a selecting arm 16, which is raised and lowered as the circuit is closed through the electro-magnet.

In the upper portion of the casing is secured a block 18 which carries a guiding device for the selecting arm. 75 This guiding device comprises two intersecting series of guide plates 20 and 21. The lower edge of each of the upper plates, and the upper edge of each of the lower plates are bent to the left, and the meeting or intersecting edges of the plates are disposed in staggered relation 80 in order to form a zigzag passage way for a pin 24 that projects from the selecting arm. At the extreme left of both series of plates is a guiding plate 25 which follows the general contour of both sets of plates and extends for some distance below the lower edges of the lower set 85 in order to form a stop or initial position of rest for the pin 24. The pin is normally held against this stop plate by a coiled spring 28, extending between the selecting arm and the arm 15.

When the selecting arm is in this initial position of 90 rest, as shown in Fig. 1, it engages a spring contact 29, and forces the same against a second contact 30 for the purpose of closing the local circuit of the subscriber with the main line, this circuit being broken, however, at the receiver hook when the latter is held down by 95 the weight of the receiver.

Secured to the base plate or other support at a point below the selecting arm guiding device are two sets of contacts 32, 33, 34 and 35, these being insulated from each other by a strip 36 formed of mica, rubber or other 100 material. These contacts are arranged at different points in the different telephones, that is to say, the contacts belonging to station No. 2 will be arranged at a point below the space between the second and third guiding plates 21. The contacts shown in Fig. 1 are arranged in 105 the space below the fifth and sixth plates. The contacts of station No. 8 would be at a point below the space between the eighth and ninth plates, and so on, and when

2
the selecting arm has been moved the proper number of times, in accordance with the station to be called, a circuit closing pin 38 carried by the arm will move down into engagement with the uppermost contact 32, 5 and will close a circuit between the contacts 32 and 33, and a second circuit between the contacts 34 and 35, thus placing the called station in communication with the line to the exclusion of all other stations.

Referring now to the diagram in Fig. 7, 50 and 51 represent the main line wires between which the stations A and B are bridged and 56 represents a switch located at the central station for the purpose of closing the selecting circuit, provision being made for sending a current in either direction, and for this purpose two batteries 52 and 53 are shown, the positive pole of one battery being connected to a switch point 54, while the negative pole of the other is connected to a switch point 55. These are placed under the control of the switch 56 and the latter is connected to the wire 50. It will be 15 understood that this arrangement is merely typical, any suitable mechanism being employed for the purpose of sending currents in one direction or the other direction as required during the selecting and restoring operations.

During the selecting operation the switch is moved into engagement with the switch point 54 a number of times corresponding to the number of the station to be called, and this will render the + pole of the electro-magnet active, and the latter will attract the armature and release the same as many times as the circuit is made and 20 broken. At the completion of this operation and after the conversation is finished, the circuit is closed through the battery 53 and the — pole of the electro-magnet attracts the armature, restoring all of the selecting devices to normal position.

35 When any subscriber wishes to open communication with another subscriber, he removes his receiver from the hook, and he is instantly connected with central station, the circuit being traced from wire 51 to wire 60, receiver hook 61, receiver hook contact 62, 40 wire 63, the secondary of the inductorium I, receiver R, wire 64, binding post 65, wire 66, wire 67, contacts 29 and 30, wire 68, to binding post 69, wire 70 to line wire 50. The subscriber then informs central of the 45 number of the station desired and central proceeds to move the switch 56 into and from engagement with the switch point 54 a number of times corresponding to the number of the desired station.

Each time the circuit is closed, the current traverses the wire 50, wire 70, binding post 69, wire 71, 50 electro-magnet 11, wire 72, wire 73, contact 74, receiver hook 61, and wire 60 of every station along the line except that of the calling subscriber, who, having removed his receiver from the hook, has broken his selecting circuit and placed the same beyond the control of the central station. As soon as this first closing 55 of the circuit occurs, the selecting arm 16 moves from engagement with the contact 29, and said contact thereupon separates from the contact 30, and the circuits of all of the subscribers along the line are disconnected, excepting that of the calling subscriber, and it is impossible for any other subscriber to open 60 communication with central until the selecting arms are again restored to initial position.

Each time the calling circuit is closed, the pin 24 65 of the selecting arm may travel upward against the

right hand face of one of the lower plates 21, and striking against the bent lower edge of the adjacent plate 20 will be deflected toward the right, and then when the magnet is deenergized, the pin will fall into engagement with the bent upper edge of the next plate 21, and will be guided down between two of the lower plates 21, but will not pass below said plates, excessive downward movement being prevented by the armature spring 13.

At the completion of the final circuit closing operation, say the fifth for instance, the final breaking of the circuit at the switch 56 will allow the pin 38 to fall into engagement with the contact 32, and the latter will be moved down for the purpose of closing two circuits, one between the contacts 32 and 33, 80 and the other between the contacts 34 and 35. The first of these is the calling circuit, which may be traced from the wire 51, through wire 60, receiver hook 61, contact 74, wire 73, the electro-magnets of the call bell 77, wire 78, contact 33, contact 32, and 85 wire 79 to ground, there being means at central also connected between the wire 51 and ground for sending a calling signal along the line and as the calling circuit of but one subscriber is closed, only the call bell of that subscriber will be sounded. The second 90 circuit is the talking circuit of the called subscriber, and when the latter removes his receiver from the hook after hearing the signal, this talking circuit may be traced from the wire 60 through receiver hook 61, contact 62, wire 63, the secondary of the inductorium, 95 the receiver, wire 64, binding post 65, wire 66, wire 80, contact 34, contact 35, wire 81, to binding post 69, wire 70, to the line wire 50, thus bridging the local talking circuit between the two main line wires.

After the conversation is finished, and the fact is 100 announced to the central station, in any manner, the central station operator moves the switch 56 into engagement with the switch point 55, sending a current over the wire 50, and this causes the electro-magnet at each station to attract the right hand end of the 105 armature 12, drawing down the selecting arm 16 until the pin 24 is below the plates 21, whereupon the spring 28 carries the selecting arm to the left, until the pin 24 engages against the end plate 25, assuming its initial position of rest, and the arm further engages 110 the contact 29 at each station and closes communication between the local talking circuit of each station and the main line, so that the line is clear for any subscriber to make a call.

I claim:—

1. In selective signaling apparatus, circuit closing contacts, an oscillatory selecting member, an electro-magnet for actuating the same, and means for guiding the selecting member in a zigzag path into circuit closing position.

2. In selecting signaling apparatus, circuit closing contacts, an oscillatory selecting member movable by gravity into engagement with the contacts, means for actuating said member, and means for guiding said member in a zigzag path into circuit closing position.

3. In a telephone selecting apparatus, circuit closing contacts, an electro-magnetically actuated selecting arm arranged to travel from the position of rest in a zigzag path toward said contacts, an electro-magnet for actuating the selecting arm, and means for guiding said arm.

4. In telephone selecting apparatus, an electro-magnetically actuated selecting arm, circuit closing contacts, and means for guiding said arm in a zigzag path from a position of rest toward said contacts.

5. In telephone selecting apparatus, an electro-magnetically actuated selecting member, contacts, and means for advancing said selecting member step by step in a zigzag path toward said contacts.
6. In selecting apparatus, an electro-magnetically actuated selecting arm having a projecting member, and a guiding means comprising a pair of sets of plates, the adjacent ends of which are bent laterally, and are disposed in staggered relation to form a zigzag path between them.
- 10 7. In telephone selecting apparatus, an electro-magnetically actuated selecting arm, a pin or lug projecting therefrom, and a pin guiding means comprising a pair of sets of angularly disposed plates having their adjacent edges disposed in staggered order, and laterally bent to form a zigzag path for the travel of the pin.
8. In telephone selecting apparatus, an electro-magnet, a polarized armature, a selecting arm carried thereby, a pin projecting from the selecting arm, a pin guiding means including a pair of sets of inclined plates having their adjacent edges bent and disposed in staggered order to form a zigzag path for the travel of the pin, contacts under the control of the selecting arm, and means for sending a selecting current in one direction during the operating of the selecting arm and for sending a current in the reverse direction to draw the pin below all of the plates and permit its return to normal position.
9. In telephone selecting apparatus, an electro-magnet having a polarized armature, a selecting arm connected thereto, a pin projecting from the selecting arm, a fixed stop with which said pin engages, a spring engaging the 25 arm and tending to hold the pin in contact with the stop, a pin guiding means formed of a pair of sets of inclined plates having their adjacent edges bent and disposed in staggered relation to form a zigzag path for the travel of the pin, means for sending a current in one direction 30 through the electro-magnet during a selecting operation, and means for sending a current in the reverse direction to withdraw the pin from all of the plates to permit its return to the initial position of rest.
- In testimony that I claim the foregoing as my own, I 35 have hereto affixed my signature in the presence of two witnesses.

WILLIAM D. WATKINS.
